UNITED STATES PATENT OFFICE.

WALTER STUMPF, OF BALTIMORE, MARYLAND.

SCREW DRIVER.

Application filed March 22, 1923. Serial No. 626,948.

To all whom it may concern:

Be it known that I, WALTER STUMPF, a citizen of the United States of America, residing in the county of Baltimore, State of Maryland, have invented certain new and useful Improvements in Screw Drivers, of which the following is a specification.

The practice of driving screws by power actuated machinery particularly by means of stationary machines has been well understood for many years as has likewise the necessity for introducing into such machines a yielding or releasing element which will prevent injury to the screw heads or splitting or other injury to the work or material by further application of turning moment after the screw is seated. While the earlier development of screw driving machines relates mostly to stationary machines, the development of the portable power driven screw drivers began at almost the same time with the flexible shaft machine and even the earlier machines included releasing means in the form of friction clutches and in some instances jaw clutches intended to give a more positive drive. Much of the screw driving apparatus described in the patents and in general use is in the form of attachments for drilling machines both portable and stationary. The problems presented in the development of screw driver attachments to drills are peculiar to that art as to arrangement, driving and rigidity, and such attachments are not generally applicable or desirable for general assembling work where one man drives screws continually and where there is opportunity for a power driven screw driver per se.

The present invention, as distinguished from the screw driver attachment art, relates to a portable electric screw driver, not intended for use as a drill, or for any purpose other than screw driving, and particularly to the combinations and arrangements of parts whereby the torque of an electric motor is applied to a screw, to drive the same and released when the operation is complete, an important feature of the invention being that the screw driving shaft or spindle, which is in several parts capable of relative motion at intervals, is directly and permanently secured to one of the gears of the usual reducing train, connecting the motor to the tool shaft, all of said parts being mounted in and guided and supported by bearings in, and rigidly secured to the

tool frame or casing, the spindle or screw driving shaft being guided and supported by an elongated bearing mounted in the tool casing, the latter being provided with a rigid extension to support and enclose the spindle and bearing which extension preferably carries at its lower end means for supporting and limiting the downward motion of the clutch and clutch shaft, which slides relatively to and releases automatically from the spindle.

In the accompanying drawings I have illustrated the essentials of a screw driving machine constructed in accordance with my invention.

In the drawing:

Figure 1, is a vertical section showing a portable electric screw driver embodying my invention in the preferred form, the section being taken on the axis of the screw driver shaft, and of the motor, showing a fragment of the motor and the end portion of the shaft in elevation. Figure 2, is a detailed view of the clutch taken at right angles to Figure 1.

Referring to the drawings by numerals, the structure shown includes a tool casing or frame 1, in which is mounted a suitable motor 2, preferably high speed and of the universal type, and suitable gearing 3, also mounted inside the casing for reducing the speed of said motor and transmitting it to the spindle 4, and a releasing device 5. The spindle comprises a hollow shaft 6, or driving member 6, which shaft is rigidly secured to the gear 7, of said reducing train of gears, 3, referred to hereinafter as the driving gear. The driving gear 7, has a central opening, 8, with a key slot 9, and the shaft 6, is provided at its upper end with a projecting stud 10, which is threaded at 11, near the end of said stud portion. The stud 10, enters and fits the central opening, 8, in the gear and is held against rotation by a transverse key, 12, seated in the stud portion and in the key slot 9. The connection is tightened by means of a nut 14, which engages the thread 11, and is screwed down against the upper face of the gear. A centering tit 15, integral with the stud projects from the end of the same and enters thrust bearing rings, 16 and 21, positioning these rings. The end thrust of the screw driving shaft is taken up by this thrust bearing 19, comprising said rings and balls 20, rolling between the rings 16 and 21, the latter resting

on the stud 10, and ring 23 and the former on the frame as aforesaid, the balls being held in position by the usual ball casing 22.

The reducing train of gears, 3, previously referred to, consists of a pinion, 25, integral with the shaft, 26 of the motor 2, the pinion and shaft being preferably supported in a suitable bearing, 27, shown in the form of a metal sleeve mounted in and on the frame 10 or casing, 1, of the tool. As shown this bearing is supported by a transverse partition or plate 29, secured between the two sections 30, and 31, of the casing 1. The pinion 25, drives a larger toothed gear 33, 15 on a stud 34, mounted in suitable bearings, 35, in the casing, which also carries a toothed pinion 37, rotating with the toothed gear 33, and of relatively small diameter. This pinion 37, in turn, meshes with the large 20 toothed gear, 7, secured to the spindle, or more particularly to the shaft 6 which is treated as a part of the spindle, the term "spindle" being used in a more general way.

It is of particular importance that all the 25 bearings referred to in the preceding paragraph are rigidly supported in the frame, and are elongated giving full support to the rotating parts. In this way all tendency of parts to get out of alignment cramping 30 or injuring the gears or the teeth is avoided. The bearing sleeve 38, previously referred to in the statement of invention page 2, line 3, et sequi, as supporting and guiding the screw driver shaft or spindle and particularly the driving member 6, thereof, is 35 rigidly supported in the frame and is of comparatively great length, fully and sufficiently guiding and supporting the tool, and eliminating any tendency to yield or 40 chatter when the tool is in operation.

Referring particularly to the composite spindle or screw driver shaft, 4, the parts 45 of which have relative motion at intervals incident to the beginning and ending of each screw driving operation, the portion of this member designated as hollow shaft 6, is provided at its lower end with jaw clutch member 42 which preferably have inclined jaw clutch engaging surfaces, 40.

The hollow 41, within the shaft, 6, is in 50 the form of a cylindrical chamber concentric with said shaft. In the upper end of this chamber is seated a helical spring, 43, which preferably fits the chamber transversely, and beneath the spring fitting the hollow there is a sliding chuck shaft, 44, normally advanced, i. e. thrust downward by said spring. This chuck shaft is hollowed 55 at 46 out from the lower end in an axial direction concentrically with the shaft to receive the screw driver bit, 47. To prevent relative rotation of the chuck as to the screw driver bit, I have shown the bit as formed with a half round end 48, giving a diametrical flat surface 49, and to provide a corre-

sponding flat engaging face on the chuck shaft, the latter has been milled transversely from the outside forming a transverse slot 90 of rectangular cross section extending substantially half way through the shaft. 70 This provides a flat surface 51, to engage the flat surface 49, of the screw driver bit 47.

The lower end of the driven or chuck shaft 44, is enlarged as to circumference, 75 forming a projecting peripheral shoulder 510, and this shoulder as shown is provided with diametrically opposite key slots, 50, extending downward from the surface 510.

To provide sufficiently hard engaging jaw 80 clutch surfaces, the chuck shaft 44, is further encircled by a hard collar, 52, which is preferably of gear steel. This collar fits the shaft and in assembling it is passed over the top end of the shaft and is pushed down 85 until it engages the shoulder, 510. The lower surface of the collar being provided with downwardly projecting lugs or keys 53, to enter and engage the key slots, 50, in the shoulder, 510.

Collar 52, is provided with upwardly disposed clutch teeth, 54 see Fig. 2, having inclined engaging surfaces 55, to engage the inclined surfaces, 40 on the hollow shaft, 6. Below the toothed portion, 56, the collar is reduced in diameter, forming a downwardly disposed peripheral shoulder 57 and a depending portion 58, of smaller diameter. The collar 52 fits closely about the chuck shaft and the mounting of the collar on the shaft is intended to be practically permanent unless the teeth 54 should be destroyed and it should become necessary to provide a new collar when the parts may be separated by heating or by means of a 90 press.

The parts, particularly the spindle and bearing described as extending downward from the driving gear 7, are housed and supported and guided within the depending extension 39, of the casing. This casing is provided at its lower end with a sheet metal cap, 59, of short cylindrical form and rounded as to its lower corners 60, the metal being turned in at the edges, 61, leaving a central opening 62, which receives and engages the reduced portion 58, of the collar freely, or in a sliding fit. The upper edge of the cap, 59, receives and encloses the lower end of the extension, 39, 110 the latter being reduced and shouldered at 63, to receive it, and the cap being fastened to the extension in any suitable manner as by means of screws, 65. The shoulder 57 on the collar 52 rests on the inside of the 115 cap and the cap serves as a support for the driver chuck shaft, the said support being opposed to the spring 43 and supporting the chuck shaft and bit when the tool is 120 not in operation. The manner in which 125 130

the screw driver bit shank enters the chuck shaft has been described, as has the manner of engaging it therein in nonrotative relation to the shaft 44. To support the screw driver bit the enlarged end of the chuck shaft is grooved circumferentially at 66, to receive a spring ring 67 and the bottom of said groove is bored radially at 68 to receive a ball 69, the bore extending into the central chamber 46. The screw driver bit is correspondingly grooved at 70 so that when the bit is thrust into place the ball engages the groove 70, being pressed by the spring 67. Rotation of the ring is prevented by tab 71 on one end thereof, the ring being preferably split, which tab, enters a small hole, 72, leading from the groove 66 inwardly.

In operation the shaft 44, is normally advanced being thrust downward by the action of the spring 43, this causes the jaw members 40 and 54 to be normally disengaged, permitting the driven shaft 44 and the screw driver bit 47, to rotate freely relatively to the hollow driving member 6 or to remain stationary as the latter rotates. As soon, however, as pressure is applied to the screw driver bit sufficient to overcome the resistance of the spring 43, the shaft recedes, i. e. moves upward into the tubular shaft 4, permitting the members 54 and 40 to become engaged, when the spindle or screw driver shaft operates, as an integral whole, rotating in response to the torque of the motor, but at a comparatively reduced speed, until sufficient resistance is encountered to overcome the spring 43, by the action of the inclined surfaces 55, sliding by one another, which again releases the chuck shaft. This operation permits the screw driver bit to be engaged with the work, the motor being previously in rotation. Pressure on the tool when the motor is rotating causes rotation of the composite screw driver shaft or spindle by engagement of the jaw clutch members, such rotation being continued until unusual resistance such as the setting of the screw causes the said members to become disengaged. The motor may then be stopped or if desired it may be continued in operation until a second screw is engaged and driven, and so on, the operation being repeated indefinitely.

The screw driver guide or centering device with which the bit is equipped consists of a sleeve 170, enclosing the lower end of the bit. This sleeve is straight and open at its lower end at 171 and of a slightly larger diameter than the bit. The upper end is provided with an internal downwardly disposed shoulder 172 providing a central opening 73 of reduced diameter and which fits the bit. At a suitable point 75 intermediate of its length the bit is grooved circumferentially and a spring ring 76 is seat-

ed in the groove. This ring 76 forms a collar on which the shoulder 72 is seated, the lower end of the sleeve 170 extending down from the shoulder to a point just above the end of the blade 77, thus the sleeve encloses the lower end of the bit and is spaced outwardly therefrom providing for the admission of a helical spring 78 which encircles the bit, resting at its upper end against the ring 76. The lower end of the bit 77 is encircled by a sliding guide member 79, which has an upper reduced portion 80 which enters the sleeve 170 engaging the spring 78 and a circular upwardly disposed shoulder 81 which engages the lower end of the sleeve 170, the reduced portion 80 of the guide member is preferably forced into the sleeve 170 to give a sufficiently permanent connection, and the lower surface of the guide member 79 is hollowed out from the bottom in an inverted frustoconical form at 82 providing for the admission and engagement of the screw heads. The conical formation provides for a variation in the diameter of the screw heads and the inverted hollow conical guide slides up and down on the screw driver bit co-operating with the blade.

It is easily apparent that the screw driver bit being centered by engagement of the cupped portion 82 of the guide with the screw head and the bit blade having entered the screw slot the tendency to disengagement of the tool with the screw slot during the driving operation is practically overcome. When the screw is seated the guide member including both the sleeves 170 and the cup portion 79, yields upwardly against the tendency of the spring 78, actuated by the pressure of the member 79 against the material into which the screw is being driven which permits the screw to be driven in flush without resistance on the part of the guide.

I have thus described specifically and in detail a portable screw driving machine embodying the features of my invention in the preferred form, in order that the nature and operation of the invention may be fully understood by those skilled in the art, however the specific terms herein are used descriptively rather than in a limiting sense, the scope of the invention being defined in the claims.

What I claim and desire to secure by Letters Patent is:

1. A portable power driven screw driver having a casing or frame, a motor secured to the frame, a screw driver shaft, a train of reducing gears one gear at one end of the train being secured to the motor shaft, a gear at the other end of the train being secured to the screw driving shaft, a portion of the casing enclosing the screw driving shaft and extending downwardly from the main portion of the casing, an elongated bearing for

- the screw driver shaft in said portion of the casing, the screw driver shaft consisting of a driving member in the form of a hollow shaft secured to said reducing gear, a chuck 55
 5 shaft inside said driving member mounted to slide and rotate relatively thereto, a spring tending to thrust said chuck shaft downwardly, the chuck shaft having a socket to receive a screw driver bit, inclined jaw
 10 clutch engaging members on the lower surface of the tubular drive shaft, inclined jaw clutch engaging members on an opposed surface of the chuck member and a support for the latter.
- 15 2. In a portable electric screw driver a casing, a motor and a screw driver spindle mounted in said casing, a reducing train of gearing connecting the motor to the screw driver spindle, bearings for the motor shaft, 60
 20 the gears and the spindle mounted in said casing, the spindle being rigidly secured to the end gear of the train, a thrust bearing for said gear and spindle, a spindle including a hollow shaft which 65
 25 is the member secured to said gear, a chuck shaft in said hollow shaft, a spring tending to thrust said chuck shaft from said hollow shaft, inclined jaw clutch surfaces at the lower end of said hollow shaft, opposed 70
 30 inclined jaw clutch surfaces on the chuck shaft and means for supporting the chuck shaft in opposition to the spring.
3. In a portable electric screw driver a motor having a shaft, a casing a screw driver spindle, a portion of the casing enclosing the spindle forming an extension of the casing, a bearing for the spindle in said extension, the spindle including a hollow shaft, a sliding chuck shaft in said hollow shaft, 75
 35 a spring tending to thrust the chuck shaft outwardly from said hollow shaft, inclined jaw clutch surfaces on the lower end of the hollow shaft, inclined jaw clutch surfaces opposed thereto on the chuck shaft.
- 40 4. In a portable electric screw driver a motor, a motor shaft, a casing in which said shaft is mounted, a screw driver spindle, a train of reducing gears connecting the shaft to the spindle, an 80
 45 extended portion of the casing enclosing the spindle, a bearing for the spindle in said extension, the spindle including a hollow shaft, a sliding chuck shaft in said 85
 50 hollow shaft, a spring tending to thrust the chuck shaft outwardly from said hollow shaft, inclined clutch surfaces on the lower end of the hollow shaft, opposed inclined jaw clutch surfaces on the chuck shaft and means for limiting the motion of the chuck shaft in response to the spring.
- 55 5. In a portable electric screw driver a motor having a shaft, a casing in which said shaft is mounted, a screw driver spindle, a train of reducing gears connecting the shaft to the spindle, a portion of the casing enclosing the spindle, a bearing for the spindle in said portion of the casing, the spindle including a hollow shaft a sliding chuck shaft in said hollow shaft, a spring tending to thrust the chuck shaft outwardly from said hollow, inclined clutch surfaces on the lower end of the hollow shaft, inclined clutch surfaces opposed thereto on the chuck shaft, said chuck shaft being hollow, a transverse slot intersecting the end of said hollow, and a bit 60
 60 having a flat surface to engage the bottom of said slot.
- 65 6. In a portable electric screw driver a motor having a shaft, a casing in which said shaft is mounted, a screw driver spindle, a train of reducing gears connecting the shaft to the spindle, a portion of the casing enclosing the spindle, a bearing for the spindle in said portion of the casing, the spindle including a hollow shaft a sliding chuck shaft in said hollow shaft, a spring tending to thrust the chuck shaft outwardly from said hollow, inclined clutch surfaces opposed thereto on the chuck shaft, said chuck shaft being hollow, a transverse rectangular 70
 65 slot intersecting the end of said hollow, and a bit having a half round surface adapted to be thrust therein, the half round portion having a flat surface to engage the bottom of said slot, a cap on the end of said extension of the frame the cap having an opening to clear the chuck shaft and a shoulder on the chuck shaft engaging the inner surface of the cap from above to limit the motion of the chuck shaft.
- 75 7. In a portable electric screw driver a casing, a motor therein having a shaft, a screw driving spindle a portion of the casing surrounding the spindle substantially throughout its length, the spindle including a hollow shaft a chuck shaft sliding in said hollow shaft a spring tending to expel the chuck shaft therefrom, the chuck shaft being hollowed to receive a screw driver bit, downwardly disposed inclined jaw clutch surfaces on the lower end of the hollow shaft, opposed inclined jaw clutch surfaces on the chuck shaft and means for limiting the motion of the chuck shaft in response to the spring.
- 80 8. In a portable electric screw driver a casing, a motor therein having a shaft, a screw driving spindle a portion of the casing surrounding the spindle substantially throughout its length, the spindle including a hollow shaft a chuck shaft sliding in said hollow shaft a spring tending to expel the chuck shaft therefrom, the chuck shaft being hollowed to receive a screw driver bit, downwardly disposed inclined jaw clutch surfaces on the lower end of the hollow shaft, opposed inclined jaw clutch surfaces on the chuck shaft and means for limiting the motion of the chuck shaft in response to the spring.
- 85 9. In a portable electric screw driver a casing, a motor therein having a shaft, a screw driving spindle a portion of the casing surrounding the spindle substantially throughout its length, the spindle including a hollow shaft a chuck shaft sliding in said hollow shaft a spring tending to expel the chuck shaft therefrom, the chuck shaft being hollowed to receive a screw driver bit, downwardly disposed inclined jaw clutch surfaces on the lower end of the hollow shaft, opposed inclined jaw clutch surfaces on the chuck shaft and means for limiting the motion of the chuck shaft in response to the spring.
- 90 10. In a portable electric screw driver a casing, a motor therein having a shaft, a screw driving spindle a portion of the casing surrounding the spindle substantially throughout its length, the spindle including a hollow shaft a chuck shaft sliding in said hollow shaft a spring tending to expel the chuck shaft therefrom, the chuck shaft being hollowed to receive a screw driver bit, downwardly disposed inclined jaw clutch surfaces on the lower end of the hollow shaft, opposed inclined jaw clutch surfaces on the chuck shaft and means for limiting the motion of the chuck shaft in response to the spring.
- 95 11. In a portable electric screw driver a casing, a motor therein having a shaft, a screw driving spindle a portion of the casing surrounding the spindle substantially throughout its length, the spindle including a hollow shaft a chuck shaft sliding in said hollow shaft a spring tending to expel the chuck shaft therefrom, the chuck shaft being hollowed to receive a screw driver bit, downwardly disposed inclined jaw clutch surfaces on the lower end of the hollow shaft, opposed inclined jaw clutch surfaces on the chuck shaft and means for limiting the motion of the chuck shaft in response to the spring.
- 100 Signed by me at Baltimore, Maryland, this 9th day of March, 1923.
